UNITED STATES PATENT OFFICE.

GEORGE N. HELFRICH, OF RICHMOND HILL, NEW YORK, ASSIGNOR TO THE UNITED STATES PRINTING & LITHOGRAPH COMPANY, OF BROOKLYN, NEW YORK, A CORPORATION OF OHIO.

DISPLAY CONTAINER.

Application filed November 21, 1925. Serial No. 70,526.

My invention relates to containers, and preferably to that type of container which is adapted for displaying as well as for shipping the articles contained therein.

The primary object of my invention is to provide a display container having a support for inclining it for better display which can be made wholly from a single integral blank.

10 Another object is to provide a display container having a support to incline it for better display and also to cover the top of the container, the whole to be made from a single integral blank.

15 Another object of my invention is to provide a display container having a support for inclining it for better display and adapted also to cover the top of the container for shipping, the whole to be formed from a single integral blank coated on one side only.

20 In order that the nature of my invention may be clearly understood, I shall first describe in detail the mode in which I at present prefer to carry the invention into practice, and then point out the various features 25 of the invention in the appended claims.

Reference is to be had to the accompanying drawings forming part of this specification in which the same parts are designated 30 by like characters in all the figures.

Figure 1 is a plan view of the blank from which I at present prefer to make my improved container.

Figure 2 is a transverse section of the container as it is shipped, its support being in position to act as an outer protective cover for the container.

Figure 3 is a transverse section of the container arranged to display the articles contained therein, the support being in position 40 to incline the container.

Figure 4 is a perspective view of the container arranged to display the articles contained therein.

45 Referring now to Figure 1, the integral blank from which I now prefer to make my improved container is denoted by numeral 6. The blank is preferably made from stock coated on one side only, and, in this embodiment of the invention, is coated on that side which forms the outside of the container when said blank is set up to form a container, so that advertising matter may be printed on the coated side.

The blank is divided into several portions, 55 the bottom portion 7, front portion 8, top portion 9, end portions 10 and 11, back portion 12, and support portion 13, which latter comprises a standard portion 14 and base portion 15. These portions, as will be understood, are integrally connected to each other and may be scored along the dotted lines shown in Figure 1.

The blank which I now prefer to use has a flap 16 integral with the bottom portion 7, 65 flaps 17 and 18 at the ends of front portion 8, and integral therewith, flaps 19 and 20 integral with end portions 10 and 11 respectively, flaps 21 and 22 integral with the ends of back portion 12, and a tongue 23 integral 70 with base portion 15, all substantially as shown in Figure 1.

At the junctions of front portion 8 with bottom portion 7 and top portion 9, I prefer to provide slits 24 and 25 respectively, for 75 purposes which will hereinafter appear.

In this instance, to provide a display card when the container is used to display its contents, I prefer to cut out the top portion 9 as shown in Figure 1. The top is cut along 80 the irregular line 26, and semi-circular line 27, so that when the cut out portion is first bent up along the line 28 and then down along lines 29, the portion 30 will serve as a display card (see Figs. 3 and 4). I also 85 choose to cut slots 31 in the cut out portion thus forming tongues 32 as shown in Figure 1, and slots 33 in the top portion 9, the purpose of tongues 32 and slots 33 being explained hereinafter.

90 In setting up the container for shipment, the flap 16 is bent up from the bottom portion 7 along line 34. The front portion 8 is then bent up along line 35, and top portion 9 bent forwardly along line 36. The 95 back portion 12 is then bent downwardly along line 28 and secured to flap 16 by paste, clips, or any other suitable means. It will be perceived that there has now been formed the bottom, sides, and top of a container.

100 Flaps 17, 18, and 21, 22 are then bent along lines 37, 38, 39, and 40 respectively, and the end portions 10 and 11 bent downwardly along lines 41 and 42 respectively. The 105 flaps 19 and 20 are then bent in along lines 43 and 44 respectively, thus forming a strong, well-built, and substantial container reinforced by the numerous flaps.

As the container during shipment and handling is subjected to various pressures, it is deemed advisable to protect the container in some manner. I choose to accom-

5 plish this result by means of the integral support portion 13, and in the following manner. After the container is set up and the desired goods inserted therein, the standard portion 14 is bent up along line 45

10 and the base portion is then bent forwardly along line 46.

The tongue 23 is then bent down along line 47 and inserted in slit 25, thus forming an outer protective cover for the container

15 in shipment (see Fig. 2).

When the container has reached its destination and is to be set up for display by the retail merchant, the tongue 23 is withdrawn from slit 25 and the support portion 13 bent 20 downwardly along line 45 instead of upwardly. The base portion 15 is then bent forwardly along line 46 and the tongue 23 inserted in slit 24 (see Figures 3 and 4). I thus form a base and standard for inclining 25 the container in order to better display its contents.

When the container is set up for display as thus described, the cut-out portion of the top 9 is bent up along line 28, and then down 30 along lines 29. The tongues 32 are then inserted in slots 33, thus supporting the display card so formed firmly in place.

It will be seen from the above description 35 that I have provided a display container and an integral protective cover therefor which may be used also as a support for inclining the container in order to better display its contents.

I attain important economies in manufacture by the use of my invention because I 40 can use a blank made from stock coated on one side only, and because I use a single

integral blank for making both the container and its combined protective cover and support.

It is evident that many changes may be made in the specific construction and arrangement described without departing from the boundaries of my invention as defined by the following claims.

I claim as my invention:

1. A container formed from a single integral blank and having a bottom portion, a front portion integral therewith and bent up from the bottom portion, a top portion 55 integral with the front portion and bent backwardly from the front portion, integral end portions bent down from the top portion, a back portion integral with the top portion and bent down therefrom, and a 60 portion integral with the back portion adapted to be bent downwardly to form a standard and forwardly to form a base to incline the container, and to be reversed to form an outer back and outer cover for the container. 65

2. A blank adapted to be bent to form a container comprising a container top portion, container end portions at each end of the container top portion and integral therewith, a container front portion integral with 70 and on one side of the container top portion, a container bottom portion integral with and on the other side of said container front portion, a container back portion integral with and on the other side of the container top 75 portion, and a portion integral with and on the other side of the container back portion and adapted to be bent downwardly to form a standard and forwardly to form a base to incline the container, and to be reversed to form an outer back and outer 80 cover for the container.

In testimony whereof I affix my signature.
GEORGE N. HELFRICH.
